UNITED STATES PATENT OFFICE.

LINCOLN E. WILKES, OF HILLSBORO, OREGON.

FEEDING MECHANISM FOR TYPE-WRITERS.

No. 838,360.

Specification of Letters Patent.

Patented Oct. 16, 1906.

Application filed August 3, 1905. Serial No. 272,676.

To all whom it may concern:

Be it known that I, LINCOLN E. WILKES, a citizen of the United States, residing at Hillsboro, in the county of Washington and State of Oregon, have invented certain new and useful Improvements in Feeding Mechanism for Type-Writers; and I do declare the following to be a full, clear, and exact description of the invention, such as will enable others skilled in the art to which it appertains to make and use the same.

This invention relates to feeding mechanism for type-writers.

The object of the invention is to improve the construction of the feeding mechanism shown and described in Letters Patent of the United States No. 575,190, granted to me January 12, 1897.

With the above and other objects in view the invention consists of certain novel features of construction, combination, and arrangement of parts, as will be hereinafter described and claimed.

In the accompanying drawings, Figure 1 is a top plan view of the machine, showing the writing mechanism left off and a book in position to be written on. Fig. 2 is a front view. Fig. 3 is a central longitudinal vertical sectional view of the same. Fig. 4 is a similar view showing a modified construction of feeding mechanism for the tension-roller.

Referring more particularly to the drawings, 1 denotes a stationary base-plate, above which is supported longitudinally-disposed side bars 2, upon which are mounted the writing mechanism of the machine, said writing mechanism being the same as shown and described in the patent hereinbefore referred to. On the base-plate 1 is adapted to be placed a book to be written on.

Slidably mounted on the upper edges of the plates or side bars 2 is a feeding mechanism by which the leaves of the book are brought to its proper position to be written upon by the writing mechanism before referred to. The feeding mechanism consists of a rectangular frame formed by parallel horizontally-disposed rack-bars 3, which are connected at their opposite ends by cross-bars 4. The cross-bars 4 may be rigidly secured to the ends of the rack-bars, as shown,

or they may be adjustably secured thereto in any suitable manner.

Midway between the ends of the side bars 2 and journaled therein is a horizontally-disposed shaft 5, on the opposite ends of which is fixedly mounted spur-gear pinions 6. These pinions are adapted to mesh with the teeth of the rack-bars 3, whereby when said shaft is turned the rectangular frame formed by said rack-bars and the cross-bars 4 is moved along the side bars 2 of the machine. Immediately above the shaft 5 and supported at its opposite ends by the side bars 2 is a strip of platen 7, on which the leaves of the book are adapted to be drawn and upon which the type-heads 8 of type-bars 9 are adapted to strike, thus forming the impression of the type on said head upon the leaf of the book.

The inner sides of the cross-bars 4 of the rack-bar frame are provided with suitable clamps 10, which are adapted to be engaged with the edge of the book-leaf to be printed, and whereby said leaf is drawn over the strip of platen when said frame is moved across the machine. In order that the leaf may be stretched taut and evenly held in position on the strip of platen, a tension device is provided, said tension device being here shown as a roller 12, which is adapted to be arranged in the fold of the leaf, as shown. The roller 12 is provided adjacent to its opposite ends with annular grooves 13, with which are adapted to be engaged hooks 14, said hooks being connected to the ends of tension-cords 15, which are adapted to be wound at their opposite ends upon tension-drums 16. These drums are provided with spiral springs 17, the tension of which is exerted to revolve the drums in a direction to wind up the cords 15. By this arrangement the book-leaf will be evenly stretched across the platen-bar while being drawn over the latter by the movement of the rack-bar frame, as hereinbefore described. The hooks 14, cords 15, and tension-drums 16 are provided on each side of the machine, so that the roller may be applied at either side of the platen-bar, thus providing for the movement of the frame in both directions to facilitate the printing of both sides of the leaf. When the rack-bar frame has been moved and the leaf of the

book drawn over the platen-strip far enough to engage the roller 12 with either side of said strip, the end of the line will be completed, at which time the mechanism is shifted to bring the parts in proper position for writing the next line.

When the hooks 14 are engaged with the roller 12 on one side of the platen-strip, the hooks 14 on the opposite side of the platen-strip are engaged with the adjacent end bars 4 of the rack-bar frame, the tension of springs controlling said latter hooks being exerted to move the frame toward this end of the machine, thus aiding in moving the leaf or sheet over the platen against the pull of the roller 12.

In addition to the above means for moving the rack-bar frame I may employ an operating mechanism similar to that shown in the patent hereinbefore referred to—that is, to mount a spiral spring 5' upon one end of the shaft 5, one end of said spring being secured to the shaft and the other to the frame of the machine. Above the upper edge of and spaced from the bars 2 is arranged a guide-strip, between which and the upper edge of the bars 2 the cross-bars 4 of the rack-bar frame are adapted to project, thereby guiding said frame, which will be moved in one direction by the unwinding of the spring, causing the rotation of the shaft 5 and gears 6, which mesh with the rack-bars 3 of the frame. The rack-bar frame is manually moved in the opposite direction and restored to its former position, this movement of the frame also winding up the spring 5', as will be understood.

The rack-bar 3 on one side of the frame will be provided on its upper side with a series of ratchet-teeth 3', which correspond with the teeth 50 on the rack-bar 42 of the patent referred to herein, and with the ratchet-teeth 3' and the rack-bar 3 will be connected a controlling mechanism for the rack-bar frame, the construction of which will be the same as that shown in said patent, and an illustration and description thereof is not deemed necessary in the present instance.

While I have shown and described the roller 12 as being held in position by tension-cords, other means may be employed for this purpose, and I do not desire to limit myself in this particular.

In order that the side bars 2 of the machine may be raised and lowered to permit various sizes of books to be inserted beneath the feeding and printing mechanism, said bars are supported upon vertically-disposed shafts 20. Said shafts are provided at their upper ends with reduced journals which bear in sockets formed in the under side of said bars. The shafts 20 project loosely through apertures formed in the base-plate 1 and are provided with screw-threads upon which are screwed pinion-nuts 21, said nuts being swiv-

eled in the plate 1 in any suitable manner, whereby when the same are turned the shafts will be screwed upwardly or downwardly, thus raising or lowering the supporting-bars 2. In order that the shafts 20 will be moved simultaneously to uniformly raise the side bars, a sprocket-chain 22 is passed around the teeth on said pinion-nuts, whereby when the chain is moved said nuts will be simultaneously turned, so that both of said supporting-plates are moved together and to the same level.

Having thus described my invention, what I claim as new, and desire to secure by Letters Patent, is—

1. A type-writing-machine feeding mechanism, having a book-support, a feeding element movable over the book-support, a platen-support over said book-support, means to attach the leaf of a book on said support to said feeding element, and means to keep said leaf under tension while said leaf is moving over the platen, substantially as described.

2. A feeding mechanism for type-writing machines comprising a base, supporting-bars arranged on said base, an impression-strip secured to said supporting-bars, a rack-bar frame slidably mounted on said bars, a revolubly-mounted drive-shaft, gear-pinions fixed on said shaft to engage and shift said rack-bar frame, means to attach the leaf or sheet to be written on with the ends of said frame, and a tension device to hold said leaf or sheet taut while being drawn over said impression-strip by said frame, substantially as described.

3. A feeding mechanism for type-writing machines comprising a base, supporting-bars arranged on said base, an impression-strip secured to said supporting-bars, a rack-bar frame slidably mounted on said bars, a revolubly-mounted drive-shaft, gear-pinions fixed on said shaft to engage and shift said rack-bar frame, means to attach the leaf or sheet to be written on with the ends of said frame, means to operate said drive-shaft and thereby move said frame and the leaf or page over the platen-strip, a tension-roller to hold said sheet or leaf taut, and means to control said tension-roller, substantially as described.

4. A feeding mechanism for type-writing machines comprising a base, supporting-bars arranged on said base, an impression-strip secured to said supporting-bars, a rack-bar frame slidably mounted on said bars, a revolubly-mounted drive-shaft, gear-pinions fixed on said shaft to engage and shift said rack-bar frame, means to attach the leaf or sheet to be written on with the ends of said frame, means to operate said drive-shaft and thereby move said frame and the leaf or page over said platen-strip and below the writing mechanism of the machine, a tension-roller to en-

gage said leaf or sheet, revolvably-mounted spring winding-drums, tension-cords loosely connected at one end to the ends of said tension-roller and at their opposite ends to said winding-drums whereby said leaf or sheet will be held taut while being moved over the platen by said rack-bar frame, substantially as described.

In testimony whereof I have hereunto set my hand in presence of two subscribing witnesses.

LINCOLN E. WILKES.
